UNITED STATES PATENT OFFICE.

GEORGE W. FRY, OF BEAVER, ASSIGNOR TO THE ROCHESTER TUMBLER COMPANY, OF PITTSBURG, PENNSYLVANIA.

DESIGN FOR A TABLE-VESSEL.

SPECIFICATION forming part of Design No. 16,546, dated February 23, 1886.

Application filed December 31, 1885. Serial No. 187,313. Term of patent 14 years.

To all whom it may concern:

Be it known that I, GEORGE W. FRY, of Beaver, in the county of Beaver and State of Pennsylvania, have invented a new and original Design for a Glass Vessel; and I do hereby declare the following to be a full, clear, and exact description thereof.

My invention consists of a glass vessel having the appearance of the hub of a carriage-wheel with the spokes cut off at or near the surface of the hub.

This design is applicable to hollow articles, such as pepper and salt dredges, tumblers, jelly-glasses, match, cigar, and other holders, and numerous other articles.

In the accompanying drawings, Figure 1 shows an elevation of a salt-dredge of my design. Fig. 2 is an elevation of a holder for cigarettes, matches, &c.

In Fig. 1, *a* is the hub-shaped body, *b* the row of short spokes, and *c* the cap. The same appearance of short spokes can be obtained by a row of similarly-shaped recesses, *d*, as in Fig. 2, instead of projection *b*.

What I claim as my new design is—

The design for a table vessel or dish herein shown and described, the same consisting in the hub-shaped vessel or dish provided with the representation of short spokes upon its outer periphery, as set forth.

In testimony whereof I have hereunto set my hand this 21st day of December, A. D. 1885.

GEORGE W. FRY.
